CLAIM

The ornamental design for an engine generator, as shown.

DESCRIPTION

FIG. 1 is a front elevational view of an engine generator showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a top plan view thereof showing the condition in which the door opened;

FIG. 7 is a front perspective view thereof;

FIG. 8 is a rear perspective view thereof; and,

FIG. 9 is a left side elevational view of reference indicating the transparent area thereof.

The claimed engine generator is a soundproof type engine generator, in which an engine driven type generator is accommodated in the condition of having stored in the bonnet. As shown in FIG. 3, a control panel is arranged at the front of the bonnet. In FIG. 9, Hatching is indicating the transparent area.
